(57) **CLAIM**

The ornamental design for an outdoor power supply, as shown and described.

DESCRIPTION

FIG. 1 is a perspective view of an outdoor power supply showing our new design;

FIG. 2 is a front view thereof;

FIG. 3 is a back view thereof;

FIG. 4 is an enlarged left view thereof;

FIG. 5 is an enlarged right view thereof;

FIG. 6 is a top view thereof;

FIG. 7 is a bottom view thereof;

FIG. 8 is an enlarged view of the encircled area 8 of FIG. 1; and,

FIG. 9 is an enlarged view of the encircled area 9 of FIG. 2. The broken lines shown on the drawings depict portions of the outdoor power supply that form no part of the claimed design. The dot-dash broken lines encircling portions of the portable power station in FIGS. 1 and 2 illustrated in enlarged views in FIGS. 8 and 9 form no part of the claimed design.
